CLAIM

The ornamental design for a shoe outsole, as shown and described.

DESCRIPTION

FIG. 1 is a bottom view of a shoe outsole showing our new design;

FIG. 2 is a rear perspective view thereof;

FIG. 3 is a bottom view of an alternative embodiment of a shoe outsole showing our new design; and,

FIG. 4 is a rear perspective view thereof.

Only the solid lines are claimed, and thus any unshaded areas demarcated in whole or in part by solid lines form no part of the claimed design. The broken lines showing the remainder of the shoe represent unclaimed subject matter and form no part of the claimed design.
